Primary Examiner—Jeffrey D Asch*Assistant Examiner*—Bridget L Eland(74) *Attorney, Agent, or Firm*—Grossman Tucker Perreault & Pfleger PLLC(57) **CLAIM**

The ornamental design for a mobile communication device, as shown and described.

DESCRIPTION

FIG. 1 is a perspective view of a mobile communication device showing the claimed design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines immediately adjacent to the shaded areas, which encompass unshaded regions, represent the bounds of the claimed design while all other broken lines are directed to environment and are for illustrative purposes only; the broken lines form no part of the claimed design.
